(57) **CLAIM**

The ornamental design for a piñata greeting card, as shown
and described.

DESCRIPTION

FIG. 1 is a front perspective view of the piñata greeting card
of the present invention.

FIG. 2 is a rear perspective view of the piñata greeting card
of FIG. 1.

FIG. 3 is a front view of the piñata greeting card of FIG. 1.
FIG. 4 is a rear view of the piñata greeting card of FIG. 1.
FIG. 5 is a left side view of the piñata greeting card of FIG.
1.

FIG. 6 is a right side view of the piñata greeting card of FIG.
1.

FIG. 7 is a top down view of the piñata greeting card of FIG.
1.

FIG. 8 is a bottom up view of the piñata greeting card of
FIG. 1.

FIG. 9 is a front perspective view of the piñata greeting card
of FIG. 1, with extended telescoping panels; and,

FIG. 10 is a front view of the piñata greeting card of FIG.
1, with extended telescoping panels.

The broken line showing of portions of the piñata greeting
card is included for the purpose of illustrating environmental
structure and forms no part of the claimed design.
